COSMETICS APPLICATOR

Samuel B. Leavin, New York, N. Y., assignor of one-third to William H. Leavin and one-third to Joseph Aversa, New York, N. Y.

Application December 15, 1954, Serial No. 475,340

1 Claim. (Cl. 15—184)

This invention relates to a cosmetics applicator. The invention applies mainly to the application of lipstick type cosmetics to the lips by means of a brush but it is equally applicable to other lipsticks which may be used directly upon the lips without the aid of a brush or other applicator. The invention also pertains to other cosmetics which may be applied either directly or by a brush, for example, eyebrow pencil, mascara and eye shadow.

The principal object of this invention is the provision of a combination holder and mechanism which houses a cosmetics applicator or a cosmetic itself and which projects it to exposed operative position and which retracts it to concealed inoperative position, a cap being provided to move it to one of these positions and a spring being provided to move it to the opposite position. The invention will hereinafter be described in terms of utilizing the spring to retract the applicator and of utilizing the cap to project the applicator to operative position but it will be understood that this is purely illustrative and the spring may be used, if desired, to project the applicator to operative position and the cap may be used to return the applicator to inoperative position.

Briefly stated, a casing is provided which has the general appearance of the barrel of a mechanical pencil. A removable cap, of the general type used in fountain pens, is removably mounted on said casing, being adapted to be slipped over either end of the casing. The back end of the casing is closed and the forward end may be tapered and open. Slidably mounted within the casing is the applicator itself or a holder for a lipstick or eyebrow pencil or the like. A spring is also mounted in said casing and it engages the applicator (or lipstick holder, etc.) and urges it rearwardly into retracted position within the casing.

A longitudinal slot is provided in the casing and a pin projects outwardly through said slot from the applicator. When the cap is slipped onto the back end of the casing, it engages said pin and pushes it forwardly, thereby carrying the applicator along with it to operative position against the action of the spring. Frictional means is provided to hold the cap in position on the casing so that the spring will not accidentally retract the applicator. When the cap is removed from the back end of the casing, the applicator is released for rearward movement under the influence of the spring to retracted position. The cap may now be placed upon the forward end of the casing to close off said end and the slot in the casing wall, thereby protecting the applicator or other cosmetic device which may be substituted therefor.

The invention is illustrated in the accompanying drawing in which:

Fig. 1 is a side view of a cosmetics applicator made in accordance with one form of this invention, showing the applicator in operative position.

Fig. 2 is a longitudinal section therethrough on the line 2—2 of Fig. 1.

2

Fig. 3 is a view similar to that of Fig. 1 but showing the device in closed position.

Fig. 4 is a longitudinal section therethrough on the line 4—4 of Fig. 3.

Fig. 5 is an exploded view, partly broken away and in section, showing the several components of the cosmetics applicator illustrated in Figs. 1 to 4.

Fig. 6 is a side view of a modified component of said device, showing a lipstick held thereby in place of the applicator shown in Fig. 5.

It will be noted in the drawing that the cosmetics applicator herein claimed includes a casing 10 and a cap 12 for said casing. The casing is generally cylindrical in form with a tapered forward end 14. It is open at both ends and is provided with a longitudinally extending slot 16 in its side wall. The back end 18 of casing 10 is normally kept in closed position or condition by means of a plug 20. Casing 10 and cap 12 are made, preferably, of metal and plug 20 is made, preferably, of molded plastics.

Cap 12 is made to be slipped over either end of casing 10. The forward end 22 of cap 12 is open and its rear end 24 is tapered and closed. A frictional fit between the cap and the casing is desired for the purposes of this invention and this is effected by means of raised ridges 26 formed on casing 10. These ridges are engageable by the cap irrespective of whether it is applied to the casing at its back end or its forward end.

Slidably mounted within casing 10 is a plunger 30, this plunger being made, preferably, of plastics molded to the shape shown in Fig. 5. It comprises a generally cylindrical body 32 with a concave recess 34 formed in its side and a transverse hole 36 formed therethrough, said hole and said recess being in communication with each other. A post or stud 38 projects forwardly from cylindrical body 32, coaxially therewith. Post 38 may have a tapered forward end 40 and an annular groove 42 encircling said tapered forward end. Since post 38 is smaller in diameter than cylindrical body 32, an annular shoulder 44 is provided between said post and said body.

It will be observed that a tubular ferrule 46 is provided and that said ferrule is somewhat tapered at its back end 48 to correspond to the taper of forward end 40 of post 38. It is consequently possible to mount said ferrule 46 on said tapered end 40 as shown in the drawing so as to secure said ferrule to said tapered end. At the forward end of ferrule 46 are hairs 50 which constitute a brush suitable for applying cosmetics.

Encircling post 38 and ferrule 46 is a coiled compression spring 52. The back end of said spring abuts annular shoulder 44. The forward end of the spring abuts the tapered end 14 of casing 10 and the spring is of such diameter relative to the opening in said tapered end of the casing that it cannot pass through. Consequently, when plunger 30 is slidably mounted in the casing, the spring acts between the tapered forward end of the casing and the annular shoulder on said plunger, thereby urging the plunger rearwardly toward the back end of the casing. Since the applicator brush is mounted on said plunger, and more particularly on its forwardly extending post 38, said applicator brush will also be urged rearwardly by said spring into retracted position within the casing.

A bowed leaf spring 60 is disposed within recess 34, its ends abutting the inside wall of casing 10. A pin 62 is secured to said leaf spring, centrally thereof, and it will be observed that said pin projects through hole 36 in the plunger and slot 16 in the casing. This pin is actually a stepped member, somewhat thicker adjacent the leaf spring and somewhat thinner at its free end. It is this relatively thin portion which projects through slot 16 as Figs. 2 and 4 clearly show. Said leaf spring functions to resiliently hold said pin in its said outwardly

projecting position, irrespective of the position of the plunger within the casing and irrespective of whether the plunger is at rest within the casing or is being moved relative thereto.

Pin 62 performs two important functions. In the first place, it serves as a stop member against the ends of slot 16 to govern the range of movement of the plunger and the brush applicator mounted thereon. By the same token, it serves as the means of locking the plunger and all of the other components connected therewith into the casing. In other words, it holds the parts together and limits their relative movement. In the second place, pin 62 is engageable by the forward end 22 of cap 12. When the cap is slipped onto the back end of the casing, it engages said pin and pushes it forwardly, thereby moving the plunger and the applicator brush forwardly to operative position, against the action of the coil spring. When the cap is removed from the back end of the casing, the pin is released and the plunger is free to return to retracted position under the influence of the spring. When the cap is now placed upon the forward end of the casing, it will once again engage the pin but this time only to assist the coiled spring in holding said pin and the plunger in retracted position.

Turning now to Fig. 6, a small variation of the above described device is shown. The entire mechanism remains the same with the exception of a modification in the plunger and a substitution of a lipstick for the brush applicator. Fig. 6 shows a plunger 76 which corresponds to plunger 30 except that it lacks a post or stud corresponding to post or stud 38 and, instead, has a cup-shaped forward portion 72 which serves as a receptacle for lipstick 74. This lipstick may be inserted directly into said cup-shaped receptacle or it may be mounted in a metal cup 76 which, in turn, would be inserted into said cup-shaped receptacle 72. This is simply illustrative of how the device herein claimed may be fitted with cosmetic preparations or cosmetic applying means in place of the brush applicator shown in the first five figures of the drawing. Another possibility, again without limiting this invention, is to substitute a cosmetic stick for brush hairs 50 in ferrule 46. There would be no change in principle and there would simply be a substitution of cosmetic applying means in the same ferrule.

The foregoing is illustrative of preferred forms of this invention and it will be understood that these forms may be modified and other forms may be provided within the broad spirit of the invention and the broad scope of the claim.

What is claimed is:

A cosmetics applicator of the character described, comprising a tubular casing which is open at its forward end, said forward end being tapered inwardly to form a generally conical shoulder on the inside thereof, a plunger

slidably mounted in said casing for longitudinal movement therein, the forward end of said plunger being reduced, an annular shoulder being formed between said reduced forward end of the plunger and the main body of the plunger, a coiled compression spring mounted on said reduced forward end of the plunger, the back end of said coiled spring bearing against said annular shoulder and the forward end of said coiled spring bearing against said conical shoulder, whereby the plunger is urged rearwardly within said casing and relative thereto, a tapered ferrule secured to the forward end of said reduced end of the plunger and adapted to project through the open tapered forward end of the casing, brush bristles held by said ferrule, a longitudinal slot formed in said casing, a transversely extending pin mounted in said plunger for transverse movement therein, one end of said pin being disposed to project outwardly through said slot, said pin being engageable with the ends of said slot to limit the longitudinal sliding movement of the plunger within said casing, a recess formed in the side of the plunger diametrically opposite the slot in the casing, a bowed leaf spring mounted in said recess, the opposite end of said pin being secured to the center of said bowed leaf spring, the ends of said bowed leaf spring being in slidable engagement with the inside wall of the casing, whereby the pin is urged by said bowed leaf spring in the direction of said slot, and a cap for said casing, said cap being removably slidably mounted on the back end of said casing and being engageable with the outwardly projecting end of said pin to push the pin and the plunger in which it is mounted forwardly against the action of the compression coil spring, thereby causing the brush bristles to project forwardly through the forward tapered end of the casing, said plunger being adapted to retract under the action of said coiled compression spring when the cap is removed from the back end of the casing, thereby retracting the brush bristles into the casing, said cap being also adapted to be placed upon the forward end of the casing in order to cover said forward end while at the same time engaging the outwardly projecting end of the pin and thereby preventing said pin, plunger and brush bristles from moving forwardly in the casing.
